UNITED STATES PATENT OFFICE

BENJAMIN FRANKEL, OF NEW YORK, N. Y.

CIGAR ACCESSORY

Application filed December 1, 1931. Serial No. 578,233.

This invention relates to cigar accessories. It is particularly directed to a highly practical and efficient piercing implement adapted to be inserted into an end of the cigar so that same may draw freely when the cigar is smoked, and it is an object of this invention to provide a piercing implement of the character described which may be inserted into the cigar at the factory directly after the cigar is finished, and which is so constructed that upon withdrawing the implement it will come out without pulling any tobacco with it or producing any dust or particles.

A further object of this invention is to provide a piercing implement of the character described, which will give the cigar in which it is inserted an appearance of increased length, and which will render it unnecessary to finish the cigar with the usual tobacco wrapper leaf which is pasted over the tip of the cigar and usually cut or bitten off by the smoker prior to smoking the cigar.

A further object of this invention is to provide a piercing implement which when withdrawn from the cigar, leaves a large, round opening, and which will puncture any lumps formed in the filler near the head of the cigar, thus insuring a perfect drawing of the cigar.

Another object of this invention is to provide a cigar having a piercing implement inserted in one end thereof, and means in the form of a wrapper, for example, a celophane wrapper, about the cigar to aid in retaining the piercing implement or borer against accidental slipping or looseness.

Still another object of this invention is to provide a neat and attractive wrapped cigar provided with a piercing implement which shall be extremely cheap to manufacture, simple to apply to or remove from the ends of the cigar without unduly breaking up the filler, and the head of which shall simulate the tip of the cigar.

Other objects of this invention will in part be obvious and in part hereinafter pointed out.

The invention accordingly consists in the features of construction, combinations of elements, and arrangement of parts which will

be exemplified in the construction hereinafter described, and of which the scope of application will be indicated in the following claims.

In the accompanying drawing, in which is shown one of the various possible illustrative embodiments of this invention.

Fig. 1 is a side view of a cigar wrapped in celophane and provided with my improved piercing implement, with parts broken away to show the interior construction;

Fig. 2 is a side view of the cigar provided with a piercing implement embodying the invention, with the wrapper removed;

Fig. 3 is a side view of a piercing implement embodying a modified construction;

Fig. 4 is a side view of still another modified construction of my piercing implement;

Fig. 5 is a side view of a further modified construction of my piercing implement;

Figs. 6 and 7 are partial longitudinal cross-sectional views of cigars having inserted therein piercing implements, illustrating further modifications of my invention; and

Fig. 8 is a side view of a still further modified form of my invention;

Fig. 9 is another side view of the structure shown in Fig. 8;

Fig. 10 is a side view of a still further modified construction; and

Fig. 11 is a cross-sectional view taken on line 11-11 of Fig. 10.

Referring now in detail to the drawing, 10 designates a wrapped cigar embodying the invention, comprising a cigar 11 into one end of which is inserted my improved piercing implement 12, the cigar and piercer being covered by a wrapper 13 which may be formed with a celophane wrapper. The usual cigar it is well known, comprises a filler composed of strips of tobacco and an outer wrapper of tobacco leaf which extends the length of the cigar, the ends of the wrapper being pasted over the tips of the cigar to prevent unraveling. The usual cigar smoker, as is well known, bites or cuts the tip at one end of the cigar to permit the smoke to be drawn through the cigar. Often the filler is formed with lumps near the head of the cigar and interferes with the free flow of smoke

through the cigar. To obviate the necessity for biting the end of the cigar and to permit the smoke to be readily drawn when the cigar is smoked, the piercing implement 12 is 5 inserted in the head of the cigar at the factory, directly after the cigar is manufactured when it is still soft and moist.

The implement 12 is provided with a head 14 and a shank 15. Preferably the shank 15 10 comprises a point 16, and a belly portion 17. The belly 17 is preferably rounded so that when the borer is withdrawn from the cigar, it comes out without pulling any tobacco with it or unduly breaking up the filler or 15 wrapper. If desired, as shown in Fig. 4, the piercing implement 20 may be provided with a shank 21 having a point 22, a conical portion or belly 23, and a second bellied portion 24. Between the bellied portions 23 and 20 24 there is preferably an inwardly curved rounded annular groove 25. The portion 26 25 between the belly 24 and the head 27 may likewise be inwardly curved to form a well rounded neck portion so that the entire shank 25 is formed of curved surfaces to permit easy withdrawal of the implement.

In Fig. 5 there is shown a piercing implement 30 having a shank formed with three bellied portions 31, 32 and 33 interconnected 30 by rounded neck portions 34 and 35. Thus the shank may be formed of any suitable length and provided with any suitable number of outwardly beaded or bellied curved portions and inwardly curved neck portions 35 forming rounded annular grooves. When the cigar seasons or dries the filler usually shrinks somewhat and separates from the rounded grooved portion between the bellied portions of the piercer. The piercer is thus 40 held tightly within the cigar without unduly gripping the shank, so that upon withdrawing the piercer it may come out cleanly without pulling any tobacco with it or producing dust or scraps of tobacco. By placing a 45 wrapper around the cigar having a piercer, should the cigar become unduly dry the wrapper 13 will nevertheless prevent accidental slipping or escape of the piercing implement from the cigar.

50 Since the piercing implement is to be inserted in the cigar at the factory after the cigar is made, said implement may be made with a head simulating the tip of the cigar so as to render it unnecessary to finish the head of the cigar, thus saving material and expense. Thus the piercer 12 may be formed with a small knob or head 14 or with a large flat head 14a, as shown in Fig. 3. As shown in Fig. 6, the cigar 11 may be formed with 55 a substantially flat end surface 11a and the tip 38 of the piercer 39 inserted into the end of said cigar may be in the form of a tip of a cigar and may be provided with a curved undersurface 40 so as not to crush the ends 60 of the tobacco strips. Thus, finishing of the

head of the cigar with tobacco wrapper leaf, is rendered unnecessary. Furthermore, the large head 38 resembling the tip of the cigar gives the cigar the appearance of increased 70 length.

In Fig. 7 there is shown a piercing implement 41 adapted to be inserted into a cigar 11 having a rounded end 11b. To this end, the piercer 41 is provided with a head 42 having a deeply curved undersurface 43 adapted to contact the curved end 11b of the cigar. This piercer 41 may be inserted by the cigar pur- 75 chaser and obviously will fit most cigars hav- 80 ing rounded tips and may be left in the cigar until it is smoked.

As shown in Fig. 4, the belly 24 of the im- 85 plement 20 is of larger diameter than the belly 13 so that upon withdrawing said im- plement from a cigar, a larger opening is made by the belly 24 to permit the belly 23 to readily pass through the opening so formed. Obviously, after any of the pier- 90 cing implements described above are removed from one end of the cigar they may be in- 95 serted into the opposite end and then with- drawn to form longitudinal openings at both ends of the cigar to permit the smoke to be readily drawn when smoking the cigar.

In Fig. 8 there is shown a piercing im- 95 plement 50 having a shank 51 formed with a flattened end 52 having notches 53 on oppo- 100 site edges thereof. The implement 50 may be inserted into the cigar and the head 54 grasped by the fingers to rotate the im- 105 plement about its axis for forming a wide cylin- drical opening. The implement 50 is es- 110 pecially useful where the cigar smoker requires an extremely easy drawing of the smoke, or for cigars which are very tightly packed with filler.

Each of the piercing implements described above may be made of wood or metal or any other suitable material, and may be colored in any suitable manner. The head, for ex- 110 ample, may have a color resembling tobacco so that the head may better simulate the tip of the cigar.

In Figs. 10 and 11 there is shown a piercing instrument 55 illustrating a still further modification of my invention. Said im- 115 plement 55 is provided with a cylindrical shank 56 formed with spaced parallel ribs or ridges 57. The implement 55 may be rotated axially before removing the same from the cigar, 120 if desired. Said ridges facilitate the inser- 125 tion and removal of the implement.

It will thus be seen that there is provided a device in which the several objects of this in- 125 vention are achieved, and which is well adapted to meet the conditions of practical use.

As various possible embodiments might be made of the above invention, and as various changes might be made in the embodiments above set forth, it is to be understood that all 130

matter herein set forth, or shown in the accompanying drawing, is to be interpreted as illustrative and not in a limiting sense.

Having thus described my invention, I claim as new and desire to secure by Letters Patent:—

1. A piercing device for a cigar or the like comprising a shank member having a longitudinally extending portion of enlarged diameter intermediate the ends thereof, the portions of said shank member at the ends of said longitudinally extending portion being of smaller diameter than the latter, said longitudinally extending portion being curved longitudinally and peripherally, and a head at one end of said shank member.
2. A piercing device for a cigar or the like comprising a shank member having a head and a pointed end, said shank member having a portion of enlarged diameter intermediate the ends thereof, said portion being curved peripherally and also longitudinally and decreasing in diameter toward both ends of the shank member whereby said shank member, when inserted into the cigar, compresses the tobacco thereof and is thereby held in the cigar.
3. A piercing device for a cigar or the like comprising a shank member having a head and a pointed end and two enlarged portions intermediate said head and pointed end, each of said enlarged portions being curved peripherally and longitudinally and decreasing in diameter toward both ends of said shank member.
4. A piercing device for a cigar or the like comprising a shank member having a head and a pointed end and two enlarged portions intermediate said head and pointed end, each of said enlarged portions being curved peripherally and longitudinally and decreasing in diameter toward both ends of said shank member, one of said enlarged portions having a smaller maximum diameter than the other enlarged portion.

In testimony whereof I affix my signature.
BENJAMIN FRANKEL.
